UNITED STATES PATENT OFFICE.

WILLIAM MONTGOMERY PERSON, OF ASHLAND, KENTUCKY.

COKE OVEN.

Application filed April 26, 1923. Serial No. 634,874.

Regenerator coke ovens with horizontal heating flues in use prior to my present invention have a series of flues, for example six arranged in a vertical tier with burners at opposite ends, the air for combustion being admitted at the end of one of the flues, either at the top or the bottom according to the direction of flow which is periodically reversed. The air and products of combustion flow in succession through the various flues and in opposite directions in adjoining flues. There are serious objections to such a heating system or arrangement as this. Thus there is great variation in the quantity of air supplied for combustion, air about one thousand percent in excess being supplied at the first burner, with the result that excess air is mixed with the products of combustion and flows therewith through the successive flues, the proper amount of air being supplied only to the last burner of the series. There is a cold zone along the length of the top and bottom flues. The ends where the burners are located are too hot because the gas burns in an excess quantity of air. Thus there is a lack of uniformity of heat distribution to the coal being coked. Again during the operation of the oven, gas is continuously admitted and because of the fact that at the time of reversal of flow of air from the regenerators there is no oxygen present for combustion due to the absence of air, and also because there is no supply of air to the burners until all the products of combustion in the system have been removed, which requires about one minute and a half, there is a waste of the constantly flowing gas which passes out of the stack unburned, and which may be approximately from seven to ten percent. The stack draft required to operate such an oven must be large because the products of combustion must be drawn through a total length of flues of about 250 feet with many reverse bends, the result being that no two flues operate under the same draft conditions. I have made my invention with the before mentioned considerations in mind and with the object, which my invention achieves, of securing uniform or substantially uniform conditions in all of the flues, avoiding waste of gas by the loss of unconsumed gas through the stack, enabling the use of a smaller stack draft, and other benefits or advantages in operation and construction which will be appreciated by those skilled in the art from the more de-

tailed disclosure of my invention which follows herein.

In the accompanying drawings:

Fig. 1 is a vertical section through enough of a coke oven to illustrate my invention; 60

Fig. 2 is a vertical section at right angles to Fig. 1;

Figs. 3 and 4 are respectively similar views of another embodiment of my invention;

Figs. 5 and 6 are respectively similar views 85 of yet another embodiment of my invention.

In the embodiments of my invention shown in the drawings the general construction and relation of flues and regenerators is about the same as now used, the regenerators, 10, being arranged in pairs beneath a coking chamber, 11, and the flues, 12, which are horizontally arranged on opposite sides of the coking chamber. Each regenerator has at the bottom a passage 13, that communicates with the stack flue, not shown in the drawing. At each end of each flue I place a gas burner, 14. Each flue is connected at each end by a channel or passage with one regenerator or the other, the same end of each flue being connected with the same regenerator so that there is a separate and independent connection or means of communication between each flue of the series and the regenerator. The channels are situated in the division walls of the oven and by suitable ports in the upper part of the regenerator communicate with the latter, and by suitable ports communicate with the flues. As shown in Fig. 1 from one of a series of ports, 15, in the regenerator a channel or riser, 16, leads to a port, 17, that opens into one of the horizontal flues so that there is a channel or riser from each regenerator to one of the ends of each flue. However, as shown in Fig. 3 the ports, 170, opening into three flues may be connected by a common riser, 160, with a single port, 150, in the regenerator so that with an ordinary arrangement of six horizontal flues there will be but two risers. The arrangement will still be 90

one where each flue has its own communication with the regenerator separate and independent of every other flue with the result that air to reach one flue or products of combustion to flow from one flue do not have to pass through another flue. As shown in Fig. 5 all the similar ends of the horizontal flues may have their ports, 171, connected by a single riser, 161, with a single port, 151, in the regenerator. And, of course, there may be 110

other groupings of a number of horizontal flues with a single rise¹ without departing from my invention.

It will be seen that whatever be the arrangement of the channels or passages which connect the horizontal flues independent of their connection with one another, that air taken into one regenerator of a pair will flow directly from such regenerator to one end of each flue, such end being the same in all the flues. Gas will be delivered to the flues through the burners at such ends and the products of combustion will pass in the same direction through all the flues and make their exit at the opposite ends of the flues into the other regenerator passing thence to the stack flue. At the time of reversal, the gas will be cut off from the burners then supplying gas, and the burners at the other ends of the flues will deliver gas thereto. The only difference in action will be the reversal of the flow of air and products of combustion through the horizontal flues. It will be seen that the conditions in each flue are substantially the same, the distribution of air to the different flues being different only to the extent that the passages from the regenerator to the end of the flues vary in length, assuming the area of the passages to be the same. Any loss by friction of the air in passing through the passages can be compensated for by increasing the areas of the longer passages and by a valve arrangement such as a slide brick, 180, which is provided to regulate the quantity of air passing through the flue. An important advantage of my invention is that the distance which the gases travel in the flues is greatly reduced over that which is necessary with the flue arrangement commonly used, which arrangement I have described. Also by my invention a much smaller stack draft is necessary. This produces a much nearer neutral condition in flues and coking chamber so that a considerable reduction of losses by leakage from oven to flues is obtained. It will also be possible to save considerable heat now going out of the stack by using longer regenerators. Another important advantage of my invention is that, say with six horizontal flues, the volume of products of combustion necessary to pass through each flue is one-sixth that required by the former construction. This result enables the number of flues to be increased and their size reduced, such that an increase in structural strength is secured which will greatly add to the life of the oven.

In the process of coking, heat is transferred to the coal being coked in two ways, by conduction and by convection. If transferred by conduction only, in a properly designed oven, each flue should transfer the same amount of heat per unit area to obtain uniform coking. But in the coking process the gases from the coal, say, opposite the bottom flue, ascend in

the coking chamber along the walls of the oven, and these walls being very hot the gases become heated and a portion of the heat is transferred to other parts of the oven as sensible heat in the gas. It is apparent that no heat is gained in the bottom flue by convection and that all the heat needed in the coking process plus the heat lost by convection must be supplied by heat from the bottom flue and regenerator. In order to get uniform coking of the coal charged, it is evident that there must be a variation of the amount of heat supplied to the coking chamber by the heat from burning fuel gas in the flues, and this varying amount must be equal to the heat lost to the ascending gases in the coking chamber. So in actual practice the heat supplied to the flues must increase from the top of the flue to the bottom, having the maximum amount in the bottom.

In my arrangement of the flues with the individual air connections for each flue it is apparent that on account of the varying length of these connections, such a distribution of air will be obtained, provided the sectional areas of the air passages are the same, but whether this proportion is the correct one there is no way of telling except by trial. This may be done by providing brick slides or dampers by which the amount of air entering the flues can easily be regulated. This adjustment of the heat conditions from top to bottom cannot be obtained in the present design of horizontal flues and can never be obtained with the vertical flue design.

By my invention heat is transferred uniformly to the coal and the coking chamber because uniform heat conditions exist in all the flues, this uniformity being accomplished by delivering the same amount of gas with the same amount of air to each flue and by removing the products of combustion through the stack draft at a uniform rate.

What I claim is:

A coking oven having a coking chamber between opposite vertical side walls, separate flues extending horizontally through said side walls, burners at the ends of said flues, a pair of regenerators directly below the coking chamber, and independent passages connecting the ends of the flues with one of the regenerators at one of said side walls and extending from the top of one of the regenerators, the passages from the top of the regenerator to the level of the flues being substantially vertical, whereby flow through said passages between the tops thereof and the top of the regenerator is substantially vertical and means connecting the other regenerator with the other ends of the said flues.

In testimony whereof I hereunto affix my signature.

WILLIAM MONTGOMERY PERSON.
